UNITED STATES PATENT OFFICE.

WILLIAM CHAUNCEY DUNWELL, OF CHICAGO, ILLINOIS.

CARD-CASE.

No. 811,489.

Specification of Letters Patent.

Patented Jan. 30, 1906.

Application filed October 2, 1905. Serial No. 281,013.

To all whom it may concern:

Be it known that I, WILLIAM CHAUNCEY DUNWELL, a citizen of the United States of America, and a resident of Chicago, county of Cook, State of Illinois, have invented certain new and useful Improvements in Card-Cases, of which the following is a full and clear specification, reference being had to the accompanying drawings, in which—

- 10 Figure 1 is a perspective view of my device, showing the case or cover folded over upon it and fastened; Fig. 2, a similar view showing the cover-flaps opened out; Fig. 3, a vertical longitudinal section on the line 3 3 of Fig. 1; 15 Fig. 4, a vertical transverse section on the line 4 4 of Fig. 3; and Fig. 5, a detailed perspective view of the metallic frame removed from the cover or case.

The object of this invention is to provide 20 an extremely simple and effectual device for holding a package of cards in such manner that they shall be protected against injury and soiling and at the same time shall be readily accessible, as more fully hereinafter 25 set forth.

To the accomplishment of this object and such others as may hereinafter appear, the invention consists of the parts and combination of parts hereinafter fully described, and 30 particularly pointed out in the appended claims, reference being had to the accompanying drawings, forming a part of this specification, in which the same reference characters designate like parts throughout the 35 several views.

Referring to the drawings by reference characters, A designates the case as a whole, which consists of a back piece, a^2 , a pair of overlapping flaps a' , connected together by 40 a separable fastener d , a transverse pocket a^4 , extending across the lower end of the casing adjacent to the shorter flap a' , and a^5 an inner thickness of material, which forms a longer pocket at the opposite or upper end of 45 the casing for the reception of the tongue-plate b^4 of the card-holding frame. The case is made of leather or other suitable material, preferably of a flexible nature.

The card-holding frame is designated as a 50 whole by the letter B and, as shown in Fig. 5, is separable from the casing, so that a new case may be attached to the frame at any time. This card-holding frame consists of a base-plate c' of substantially the same width

and length as the main part a^2 of the case, 55 side flanges c^2 , and an end flange b^3 at the upper end of the plate c' , these flanges being connected and bound together by a transverse overhanging flange b , whose ends b^2 are folded down upon the side flanges c^2 and fastened by solder or otherwise, thus forming a box-like holder at the upper end of the frame. The fastening-tongue b^4 is attached to the frame at its upper end and extends downwardly substantially parallel with the base-plate and toward its lower end, so that it may be inserted in the pocket at the upper end of the casing.

Fastened to the upper side of the lower end of the base-plate is a spring-plate c , which is 70 substantially the same width and length as the base-plate and has its upper end lying between flanges c^2 and projecting in under the overhanging flange b , against the under side of which the free upper end of the spring-plate normally bears. The connected ends of the base-plate c' and the spring-plate c are 75 removably inserted in the transverse pocket a^4 of the case, thereby securely attaching the card-frame to the case. 80

It will be observed that the package of cards H is attached to the card-frame by simply forcing the upper end of the package in under the hood or flange b , the spring c yielding sufficiently to permit the cards to pass 85 under the flange and having sufficient elasticity to resiliently clamp the cards up against the under side of the flange. By the use of the broad flat spring-actuated plate c and the side flanges c^2 the cards are held securely in place with but a slight pressure, and thus holding the cards by a slight pressure enables them to be withdrawn one at a time without injury or defacement. 90

It is obvious that I may employ a spring 95 under the plate c to actuate it or reinforce its action without departing from the invention in the least.

Having thus fully described my invention, what I claim, and desire to secure by Letters Patent, is—

1. In combination with a casing or cover, of a metallic card-frame consisting of a base-plate having a box-like device at its upper end, this device embodying side flanges and a transverse flange, a broad, flat, spring-actuated clamp-plate attached to the lower end of the base-plate, and extending in under said

- flanges and normally bearing up against the inner side of the same, and means for attaching the card-frame to the case or cover.
2. In combination with a flexible case or cover provided with a pocket across its lower end and another pocket at its upper end, of a card-frame comprising a base-plate having a tongue b^4 at its upper end adapted to enter said pocket at the upper end of the case, the lower end of the base-plate being adapted to

enter the other pocket carried by the case, and card-holding means carried by the base-plate.

In testimony whereof I hereunto affix my signature, in the presence of two witnesses, 15 this 28th day of September, 1905.

WILLIAM CHAUNCEY DUNWELL.

Witnesses:

CHARLES H. BINNEY,
JAMES C. BAKER.
